UNITED STATES PATENT OFFICE.

JACOB BENEDICT, OF GRAND RAPIDS, MICHIGAN, ASSIGNOR OF ONE-HALF
TO THE EMPIRE WRINGER COMPANY, OF AUBURN, NEW YORK.

WASH-BENCH.

SPECIFICATION forming part of Letters Patent No. 240,078, dated April 12, 1881.

Application filed December 18, 1880. (No model.)

To all whom it may concern:

Be it known that I, JACOB BENEDICT, of Grand Rapids, in the county of Kent and State of Michigan, have invented certain new and useful Improvements in Wash-Benches; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

Figure 1 is a vertical section of my folding wash-bench. Fig. 2 is a side view of the same folded. Fig. 3 is a section on the line xx , Fig. 1. Fig. 4 is a view of the outer side of the wringer-standard. Fig. 5 is a vertical section through one of the central legs. Fig. 6 shows front and side views of one of the central legs. Figs. 7 and 8 are perspective views of the clamping-plates, and Fig. 9 shows detail views of one of the outer legs and side pieces with their connecting-clamp.

The object of my invention is to provide simple, durable, and effective clamping devices or fastenings for the frame of a folding wash-bench and wringer; and the invention consists in a socketed locking-clamp, and in other details of construction, as hereinafter more fully described and claimed.

A represents one of the wringer-standards, which are connected by the cross-pieces a and a' . On the inner side of each standard is a short semicircular trough, B, that is arranged below the ends of the wringer-rolls B' B', to prevent the water from dripping to the floor and direct it to the water-board C, that is supported on the wire bracket C' and on one of the pins c c'. This water-board is reversible, so as to incline to either side, as required, and is held in place by the projecting ends of the cross-piece c', which rests against the sides of the wringer-standards.

The lower end of each standard A is recessed to fit in the central socket of the metallic clamp D. (Shown in Figs. 2 and 7.) This clamp is provided with projecting flanges forming five sockets, the central one, d, being for the lower recessed end of the wringer-standard,

and having formed just above it a transverse ridge or tongue, d', that enters a corresponding slot, b, in the outer side of the standard A, and thus assists in holding it in place.

The central or stationary legs, E E, are formed to fit into the sockets e e, and are provided with grooves e' e', that receive the corresponding tongues e² e² in the lower edge of said sockets. They are also further secured by means of the bolts e³. 60

The side pieces, F F, forming the table or bench-frame, are pivoted in the outer sockets, f f, of the clamp D, and are each provided on one side at the inner end with an elongated slot, f', that receives the pin f², and on the under surface with a transverse slot or groove, f³, that engages with the tongue f⁴ at the outer edge of the socket f. 65

To the outer end of the side piece, F, is secured a metallic clamp or socket, G, provided at the top with upward-projecting edges g g, that clasp the side of the piece F, and on its inner side with a rim, g', that serves to prevent the pivoted legs H from slipping inward when the bench is unfolded for use. The legs H are sufficiently beveled at each end so as to incline outward when the bench is unfolded, and at the same time rest firmly and evenly on the floor and against the under surface of the side pieces, F F. Each of these legs is provided with an elongated slot, h, that receives a bolt, h', passing through the socket G. They are also connected with those on the opposite side by the braces h². 80

On the inner side of each standard A, and connecting the stationary legs E E, to which it is secured by means of the bolts e³, is arranged the metallic clamp I. (Shown in Figs. 1 and 8.) This clamp is provided with a flanged socket, i, having on each side and at the bottom a ridge or tongue, i', that enters a groove, k, in the ends of the girt K, which rests in the sockets i i and extends between the two sides of the bench. The back of the plate I when in position forms the inner sides of the sockets 90 in the plate D, and the two plates clamp the standards A and legs E firmly together. 95

When the side pieces, F, and pivoted legs H are folded up against the standards A, as shown in Fig. 2, the inner or lower end of each 100

side piece, F, presses inwardly against the projecting flange that forms one side of the socket in the end of the plate D, and being also held by the pivot or pin f^2 , no other fastenings are required. The usual necessity of employing hooks or equivalent fastenings to hold the pivoted parts of the bench in position when folded is thus obviated.

In order to fold or unfold the frame it is only necessary to raise and draw the side pieces, F, slightly upward and outward, so as to cause the slot f^1 to move on the pin f^2 .

By means of the metallic clamping-plates D and I and the sockets G, the standards, side pieces, and legs of the wash-bench are firmly united in such a manner that they may be readily detached from each other and from the girt K whenever desired. The various parts may thus be closely packed, so as to occupy but a small space.

The bench-frame when unfolded for use is rigidly braced, and affords a firm support for use as a wash-bench and wringer.

Having thus described my invention, what

I claim as new, and desire to secure by Let- 25
ters Patent, is—

1. The combination, with the standards A, legs E, pivoted side pieces, F, and legs H, of the metallic clamping-plate D, having sockets $d e f$ and pivots f^2 , substantially as specified. 30

2. The combination of the socketed clamping-plates D I, pivoted side pieces, F, sockets G, and legs H, substantially as shown and described.

3. The combination of the standards A A, 35
legs E E, outer clamping-plate, D, having
sockets $d e f$, inner clamping-plate, I, having
tongued socket i , and the cross-girt K, resting
in the sockets i and connecting the opposite
sides of the bench, substantially as set forth. 40

In testimony that I claim the foregoing as my own I have hereto affixed my signature in presence of two witnesses.

JACOB BENEDICT.
